UNITED STATES PATENT OFFICE.

DAVID HINDAHL, OF CHICAGO, ILLINOIS, ASSIGNOR TO RODGER BALLAST CAR COMPANY, OF CHICAGO, ILLINOIS, A CORPORATION OF MAINE.

DUMP-CAR.

1,374,567.

Specification of Letters Patent. Patented Apr. 12, 1921.

Application filed February 21, 1919. Serial No. 278,338.

To all whom it may concern:

Be it known that I, DAVID HINDAHL, a citizen of the United States, residing at Chicago, in the county of Cook and State of Illinois, have invented certain new and useful Improvements in Dump-Cars, of which the following is a specification.

This invention relates to dump cars, and more particularly to dump cars which are convertible from a hopper bottom to a flat bottom arrangement, and vice versa.

In the regular Hart convertible car, as shown in his Patent No. 827,632, granted July 31, 1906, the end pieces of the car shown are solid and are movable in position from the end of the car to the end of the hopper in a manner to form the end structure of the hopper when the car is being used for center dump work. There are certain advantages in permanently securing the solid end pieces in place at the ends of the car. On the other hand, it is advantageous to have removable members which may form the end structures of the hopper when the car is being used for center dump work. Referring again to the Hart patent in question, it will be noted that floor doors are shown which cover the hopper when the car is used as a flat bottom car, said doors being swung upwardly and outwardly to form continuous hopper portions when the hopper bottom arrangement is desired. The hoppers must be covered when it is desired to convert the car into a flat bottom car and at the same time the removable hopper ends must be shifted from their normal positions in order to present an unobstructed flat floor portion through the length of the car.

By my present invention, when it is desired to form a flat bottom arrangement, the hopper and structures are removed from their normal positions and placed over the parts of the hopper, to present a flat floor, the remaining part of the center hoppers being covered by pivotally mounted floor members which when the car is arranged as a hopper bottom car occupy a position on the floor between the ends of the car and the removable hopper ends. The sides of the car may be moved from a vertical position in which they are mounted when a flat bottom arrangement is used to an inclined position wherein they form portions of the hopper walls.

The object of this invention is to simplify

and improve convertible cars in a manner whereby various parts thereof perform a plurality of functions, and coöperate in a novel manner to meet the requirements for successful commercial use.

These and other objects are accomplished by means of the arrangement disclosed on the accompanying sheets of drawings, in which—

Figure 1 is a fragmentary side elevation of a convertible car embodying my invention,

Fig. 2 is a longitudinal sectional view of the same car showing a flat bottom arrangement.

Fig. 3 is a fragmentary plan view of the same car showing the flat bottom arrangement,

Fig. 4 is a fragmentary plan view showing the hopper bottom arrangement.

Fig. 5 is a transverse sectional view showing the hopper bottom arrangement, and

Fig. 6 is a transverse sectional view showing the flat bottom arrangement.

The various novel features of my invention will be apparent from the following description and drawings and will be particularly pointed out in the appended claims.

Referring to the figures of the drawings, it will be noted that I have provided a dump car including sides 10, ends 11 and a bottom including fixed horizontal portions 12 at the ends of the car. Intermediate the fixed portions 12, the bottom of the car is provided with a central hopper 13 including a dump door 14, by means of which the load, or a portion thereof, may be dumped between the rails. The load also may be dumped to the outside of the rails by moving the floor doors 15 into an open position, thereby providing for side ballast work in addition to center ballast. Normally the floor doors 15 occupy a horizontal position and extend the entire distance between the stationary floor portions 12.

When the car is arranged as a hopper bottom car, the side members 10, which in one position form vertical side portions of the car, occupy inclined positions substantially in the same planes with the hopper dump door 14 and its coöoperating hopper member 16, respectively. These side members 10 which are adjustable from their vertical position, shown in Fig. 6, to an inclined position, shown in Fig. 5, are supported at their

lower ends by suitable angle members 17, their upper ends being supported by side sheeting 18 forming a closure for the sides of the car at the upper ends thereof when 5 the side members 10 are in inclined position. These side members 10 preferably are not pivotally connected to the side structure of the car, but, on the other hand, are free 10 separate pieces. It will be noted that the central hopper 13 is not provided with the usual pivotally mounted doors for covering the hopper when the car is arranged as a flat bottom car.

In this connection I have provided members 19 which perform two separate and distinct functions. As shown in Fig. 4, the member 19 forms an end wall for the central hopper 13 and separates the stationary floor portion 12 from the hopper portion of 20 the car. When the car is arranged as a flat bottom car, the member 19 acts as a floor portion (see Figs. 2 and 3) which lies in a horizontal position and covers part of the central hopper 13, one end of the member 25 19 in such position being located at the transverse center-line of the car, the other end of the member 19 extending toward the end of the car. The remaining portion of the hopper 13 at each end, with the flat bottom arrangement, is covered by a pivotally mounted member 20, the swinging edges of which abuts the outer end of the member 19 forming a horizontal flat floor throughout 30 the entire length of the car, it being understood that there are two members 19 and two members 20 for forming the complete cover for the hopper portion 13 of the car. When the car is arranged as a hopper bottom car, each of the pivotally mounted members 20 is swung from a position over the 35 central hopper 13, as shown in Figs. 2 and 3, into the position shown in Fig. 4, in which position the member 20 occupies a portion of the stationary floor portion 12.

40 As shown in Fig. 4, the car is arranged as a hopper bottom car, the member 19 occupying a position wherein it forms an end wall for the central hopper 13. In this connection it is understood that when the car is arranged as a hopper bottom car for carrying dumpable material, unless some separating means is provided, the dumpable material not only occupies the hopper portions of the car, but also accumulates and 45 occupies the fixed horizontal portion 12 at the ends of the car. The members 19, therefore, when forming hopper end walls, prevent accumulation of dumpable material on the fixed horizontal floor portions 12, there- 50 by obviating the necessity of shoveling dumpable material from the fixed floor portions. It is well appreciated that certain classes of merchandise cannot be carried to 55 advantage when the car is arranged as a hopper bottom car, there being many ad-

vantages in making the car convertible into a flat bottom car in connection with carrying certain lines of merchandise. The movable members 19 and 20, together with the movable side members 10, make changing 70 the car from a hopper bottom car to a flat bottom car, and vice versa, a very simple matter.

There may be various modifications of my invention as herein particularly shown 75 and described, and it is my intention to cover all such modifications which do not involve a departure from the spirit and scope of the invention as set forth in the following claims.

I claim:

1. A car of the class described, having a hopper, the end cover sections of which hopper are changeable in position to enable them to serve as portions of the flat floor of 85 the converted car, said sections or portions in either position being arranged in a horizontal plane.

2. A car of the class described, having a hopper, stationary flat floor portions at the 90 ends of the car, a flat floor covering said hopper, portions of said flat floor being changeable from their positions over the hopper to a flat horizontal position over the said end floor portions.

3. A car of the class described, having a longitudinal hopper, detachable vertical side walls movable entirely free from the sides of the car, and means for supporting said detachable side walls in inclined position to 100 form a portion of the hopper sides.

4. A car of the class described, having a central longitudinal hopper, portions of the hopper walls being formed by floor portions covering the hopper in one position and by 105 detachable side walls movable entirely free from the sides of the car.

5. A dump car including sides, ends and a bottom which may be converted from a dumpable hopper bottom to a flat bottom, 110 a portion of the bottom at all times remaining fixed, and a vertically arranged hopper end member separating said fixed portion from the other portion of the car, said member being movable and in one position forming a cover for a portion of the hopper.

6. A dump car including sides, ends and a bottom which may be converted from a dumpable hopper bottom to a flat bottom, 115 and a movable member which in one position forms a vertical hopper end wall and in another position forms a cover for a portion of the hopper.

7. A dump car including sides, ends and a bottom which may be converted from a 125 dumpable hopper bottom to a flat bottom, a movable member forming in one position a vertical hopper end wall intermediate the ends of the car and in another position a cover for a portion of the hopper, and an 130

additional member coöperating with the other member to form a cover for an end portion of the hopper.

8. A dump car including sides, ends and a bottom which may be converted from a dumpable hopper bottom to a flat bottom, a member which in one position forms a vertical hopper end wall intermediate the ends of the car and which in another position forms a cover for a portion of the hopper, and an additional member which in one position coöperates with said other member for forming a cover for another portion of the hopper and which in another position is located between the car end and its associated member when said associated member is in a position to form a hopper end wall.

9. A dump car including sides, ends and a bottom which may be converted from a dumpable hopper bottom to a flat bottom, a portion of the bottom at all times remaining fixed, a member which in one position forms a hopper end wall separating said fixed portion from the other portion of the car, said member being movable and in another position forming a cover for a portion of the hopper, and an additional member which in one position coöperates with said other member for forming a cover for another portion of the hopper and which in another position is carried by the fixed bottom portion.

10. A dump car including sides, ends and a bottom which may be converted from a hopper bottom to a flat bottom, the sides of the car being movable from vertical position into an inclined position to form hopper side wall portions, and a movable member which in one position forms a hopper end wall and in another position forms a cover for a portion of the hopper.

11. A dump car including sides, ends and a bottom which may be converted from a hopper bottom to a flat bottom, the sides of the car being movable from vertical position into an inclined position to form hopper side wall portions, a movable member which in one position forms a hopper end wall and in another position forms a cover for a portion of the hopper, and an additional member forming another portion of the hopper cover.

12. A dump car including sides, ends and a bottom which may be converted from a dumpable hopper bottom to a flat bottom, a portion of the bottom at all times remaining fixed, the sides of the car being movable from a vertical position into an inclined position to form hopper side wall portions, and a hopper end member separating said fixed portion from the other portion of

the car, said member being movable and in one position forming a cover for a portion of the hopper.

13. A dump car including sides, ends and a bottom which may be converted from a dumpable hopper bottom to a flat bottom, the sides of the car being movable from one position into another position to form hopper side wall portions, and a movable member which in one position forms a hopper end wall and in another position forms a cover for a portion of the hopper.

14. A dump car including sides, ends and a bottom which may be converted from a dumpable hopper bottom to a flat bottom, the sides of the car being movable from a vertical position into an inclined position to form hopper side wall portions, a movable member forming in one position a hopper end wall and in another position a cover for a portion of the hopper, and an additional member coöperating with the other member to form a cover for another portion of the hopper.

15. A dump car including sides, ends and a bottom which may be converted from a dumpable hopper bottom to a flat bottom, the sides of the car being movable from a vertical position into an inclined position to form hopper side wall portions, a member which in one position forms a hopper end wall and which in another position forms a cover for a portion of the hopper, and an additional member which in one position co- operates with said other member for forming a cover for another portion of the hopper and which in another position is located between the car end and its associated member when in a position to form a hopper end wall.

16. A dump car including sides, ends and a bottom which may be converted from a dumpable hopper bottom to a flat bottom, a portion of the bottom at all times remaining fixed, the sides of the car being movable from vertical position into an inclined position to form hopper side wall portions, a member which in one position forms a hopper end wall separating said fixed portion from the other portion of the car, said member being movable and in another position forming a cover for a portion of the hopper, and an additional member which in one position coöperates with said other member for forming a cover for another portion of the hopper and which in another position is carried by the fixed bottom portion.

Signed at Chicago, Illinois, this 17th day of February, 1919.

DAVID HINDAHL.
